(57) **CLAIM**

The ornamental design for a hybrid seal member, as shown and described.

DESCRIPTION

FIG. 1 is a perspective view of a hybrid seal member showing my new design;

FIG. 2 is a front elevation view thereof, with the rear elevation view being identical thereto;

FIG. 3 is a right side elevation view thereof, with the left side elevation view being identical thereto;

FIG. 4 is a top plan view thereof, with the bottom plan view being identical thereto;

FIG. 5 is a cross-sectional view thereof, taken along lines "I-I" of FIG. 4; and,

FIG. 6 is an enlarged view of area "II" of FIG. 5.

1 Claim, 4 Drawing Sheets

FIG. 1

FIG. 2

FIG. 3

FIG. 4
